UNITED STATES PATENT OFFICE.

ELMER R. CORWIN, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONE SYSTEM.

1,040,633.

Specification of Letters Patent.

Patented Oct. 8, 1912.

Application filed January 18, 1909, Serial No. 472,860. Renewed May 4, 1911. Serial No. 625,089.

To all whom it may concern:

Be it known that I, ELMER R. CORWIN, citizen of the United States, residing at Chicago, in the county of Cook and State 5 of Illinois, have invented a certain new and useful Improvement in Telephone Systems, of which the following is a full, clear, concise, and exact description, reference being had to the accompanying drawings, forming 10 a part of this specification.

My invention relates to telephone exchange systems, and has a number of objects and advantages which will appear by reference to a description of the preferred 15 embodiment thereof, shown in the accompanying drawing, that illustrates two telephone lines each extending to multiplied jack switches at an exchange. Each telephone line includes two limbs 1, 2 that extend from sub-stations to an exchange, the lines being shown as terminating in jack switches 3, 3 at the exchange. The apparatus illustrated at each sub-station includes a telephone switch-hook 4, a telephone receiver 5, a transmitter 6, an impedance coil 7, a call bell 8, and a condenser 9, the switch-hook, when supporting the receiver, including the bell and condenser in bridge of the line, and, when free of the receiver, including 20 said receiver and transmitter in series with the telephone line and each other and the impedance coil 7 in shunt of the receiver.

I do not limit myself to the particular 35 style of sub-station employed, as other outfitts may be used without departing from the spirit of my invention.

The limb 1 of each line includes an impedance coil 10 at the exchange, which is 40 interposed between one pole of the common battery 11 and the connection of said limb with the jack switch terminals. Both limbs of each telephone line terminate in jack switch contacts of the multiple jacks. A 45 third jack contact is provided for each jack switch for testing purposes, this jack contact being in the form of a test thimble 31, the contact thimbles of the jacks associated with each line being commonly connected with one terminal of a cut-off relay 12, the other terminal of which is connected with that pole of the battery 11 which is companion to the battery pole that is connected with the line 1. A line signal 13 is in serial 50 relation with the limb 2 of each telephone line, the battery 11 and the armature switch of the cut-off relay 12, the signal 13 being located between the battery 11 and the connection of the corresponding limb 2 with the jack switches. 55

When a subscriber initiates a call, he closes circuit of the battery 11 through the line signal 13, the unattracted armature switch of the cut-off relay 12, his switch-hook, the receiver 5 and the transmitter 6 60 and the impedance coil 7, together with the limbs 1, 2 of his line, whereby circuit is established through the line signal 13, which is preferably a small incandescent lamp, for the purpose of energizing the same to notify 65 the operator that a connection is desired. The apparatus which the operator employs for answering a calling subscriber and connecting him with a called subscriber, includes the cord circuit having an answering 70 plug 14 provided with three contacts, a tip contact, a sleeve contact, and a thimble contact, and a connecting plug 15 provided with contacts similar to the contacts of the answering plug 14, the tips of the plugs 75 14, 15 being adapted to be united for the purpose of passing telephonic currents, while the sleeves of said plugs 14, 15 are similarly united, the heel contacts of said plugs, however, being adapted for inclusion in local 80 circuits that are rendered independent of each other by means of the condensers 16 and 17 in the talking strands, the tip and sleeve strands, of the cord circuit. A relay 85 18 is connected with that portion of the tip strand intervening between the condenser 16 and the tip of the answering plug, this relay 18 being connected with the upper terminal of the battery 11 and having an armature switch which is adapted positively to open 90 or positively to close one gap in the circuit of the self-restoring clearing-out indicator 19, there being preferably but one clearing-out indicator in the system of my present invention, the clearing-out indicator being 95 desirably in the form of a small incandescent lamp. When an operator has inserted the answering plug 14 into the jack of a calling line, a circuit is at once established 100 for the relay 18, which may be traced from the upper terminal of the battery 11, through the winding of the relay 18, the tip contact of the answering plug, the tip contact of the answering jack into which 105 said plug is inserted, the switch-hook, re- 110

ceiver, transmitter, and impedance coil at the calling subscriber's station, back to the lower terminal of the battery 11, whereby the clearing-out signal 19 is not operated when the calling subscriber is responded to by the operator. The operator's telephone outfit 20 is thrown at once into connection with the calling line, by reason of the armature switch 21 of the relay 22, when unattracted, said armature switch 21 having two contacts connected one with the tip and the other with the sleeve strand of the cord circuit, and, when unattracted, engaging two contacts which constitute the terminals of the operator's telephone set.

It will be observed that there is but one pole of the battery 11 connected with a talking strand of the cord circuit, the other pole of the battery being directly connected with a limb of each of the lines, so that the battery is fed to the lines not by way of both strands of the cord circuit, but by way of one of the strands of the cord circuit to one limb of the line and directly to the other limb of the line, this arrangement being provided inasmuch as I have caused the receivers of the operators' telephone sets normally to be connected in bridge of the cord circuits. It will be observed that inasmuch as the battery is not connected with both sides of the cord circuits, but is connected in the manner specified, cross talk is impossible even though the operator's telephone outfit is normally connected with the cords.

Having ascertained the wants of the calling subscriber, by reason of the described association of the operator's telephone set with the calling telephone line, the operator tests the jack switch of the called line by holding the tip of the connecting plug 15 against the test thimble of the jack of the called line appearing before her, an audible test following if the called line is busy and no manifestation occurring if the called line is idle. The circuit that is established when the called line is busy may be traced from the upper terminal of the battery 11, through the winding of the test relay 23, the induction coil winding 24 that is in inductive relation with the induction coil of the operator's telephone outfit, the normal contact of the armature switch 25, the normal contact of the armature switch 26, the tip contact of the testing plug, the thimble of the jack that is being tested, thence to the thimble of the jack into which a plug is inserted at another section of the multiple board, the thimble contact of the plug inserted into such jack at such other section of the multiple board, and either through the line of the called party, back to the other terminal of the battery 11, if the called party then happens to have his telephone off of its hook, or back to said remaining terminal of the battery 11 by way

of the contact switch 27 and its normal contact and the winding of the relay 22, if the subscriber of the busy called line has not yet removed his telephone from its hook. The circuit of the test magnet 23 includes its own armature and contact, the armature of said magnet 23 thus vibrating when the tip of a testing plug, in finding a busy line, establishes circuit through said test magnet, whereby the coil 24 of the induction coil is intermittently included in circuit, thereby to convey to the operator a characteristic signal which informs her that the called line is busy. If the called line is idle, there is no path-way to the lower terminal of battery 11, which includes the test magnet 23, and therefore no sound is occasioned in the operator's receiver as a consequence of the test. If the line tested has been found idle, the connecting plug 15 is inserted in the jack of the called line, whereupon the magnet or relay 22 is energized, causing an attraction of the armature switch 21 to remove the operator's telephone outfit from circuit, the last function of this outfit having been served when the test had been concluded. The circuit that is established for the purpose of energizing the relay 22 may be traced from the lower pole of the battery 11, through the winding of said relay, the armature switch 27, its normal contact, the thimble contact of the connecting plug 15, the thimble of the engaged jack of the called line to the upper terminal of the battery 11, the circuit thus traced including the cut-off relay 12 so as to cause its energization and thereby to prevent the line signaling lamp 13 corresponding to the called line, and which may be located at another section of the board, from glowing when the called subscriber responds to the signal that is occasioned at his station automatically, as will now be described. The right-hand armature switch 25 of the magnet 22 is attracted when the armature switch 21 is attracted, thereby first to exclude the test magnet 23 and test coil 24 from circuit, the alternate contact of the armature switch 25 then being engaged to connect the calling generator 26¹ with the line, so as to enable the transmission of current from said generator to the signal bell 8 of the called line. The circuit of the generator 26¹ may be traced from the ground shown below the battery 11, through the generator, the alternate contact of the armature switch 25, the normal contact of the armature switch 26, the tip contact of the connecting plug 15, the tip line spring of the jack engaged by said plug tip, the bell 8, the condenser 9, to the grounded impedance 10.

A constantly rotating two-part drum 29 has borne upon it two brushes 30 that are in the calling generator circuit, one of the parts of the drum 29 being in the form of a semi-

cylindrical contact segment, while the other part of said drum is in the form of a semi-cylindrical segment of insulating material, the two segments together constituting the 5 cylindrical drum, the drum thus being adapted intermittently to open and close the generator circuit, so that the bell 8 is caused intermittently to ring. When the called subscriber responds to the signal thus conveyed, he removes his telephone from its switch-hook, and thereby substitutes for the condenser 9 a continuous path section for current from the battery 11, for the purpose of energizing the relay winding 31 to 10 occasion the exclusion of the generator 26¹ from circuit with the called line in the manner to be described. In order to keep the battery 11 and the generator 26¹ in separated relation, while affording means for permitting 15 the battery 11 to be included in circuit with the winding 31, I employ brushes 32 that rest upon a drum 33 that is similar in construction to the drum 29 and which is driven at the same rate of speed, the brushes 20 resting upon each drum being in contact with the metallic segment thereof, while the brushes of the other drum are upon the insulating segment thereof. When the brushes 25 rest upon the metal segment of the drum 33, the called subscriber having responded by removing his receiver from its switch-hook, circuit may be traced from the upper terminal of the battery 11, the brushes 32, the winding 31, the normal contact of the 30 armature switch 26, the tip of the connecting plug, the corresponding terminal of the engaged jack, the called telephone line, to the lower terminal of the battery 11. The winding 31 being thus energized, causes the 35 attraction of the various armature switches 28, 34 and 35, the switches 28 and 34 engaging alternate contacts in order to complete the tip and sleeve strands of the cord circuit. When the armature switch 35 is attracted, it 40 connects one terminal of the winding of the magnet 36 which controls the armature switches 26, 27 with the upper terminal of the battery 11, the other terminal of the winding 36 being connected with the other 45 terminal of the battery 11 by way of a portion of the sleeve strand of the cord circuit, the sleeve contact of the connecting plug, the corresponding contact of the engaged jack of the called line, and the impedance coil 10 of the called line. Circuit having thus been 50 established through the magnet 36, its armature switches 26, 27 are attracted, whereby circuit conditions are brought about now to be described. The coil 31 has its circuit 55 opened at the switch 26, but the coil 37 upon the same core with the coil 31 has its circuit closed by a contact of armature switch 34, so that the armature switches 28, 34 and 35 are still attracted. The energizing circuit 60 for the magnet 22 and cut-off relay 12 which

was previously traced, is opened at the normal contact of the armature switch 27, but circuit for the magnet 22 is immediately re-established at the alternate contact of the armature switch 27, which new circuit may 65 be traced from the lowermost pole of the battery 11, the winding of the magnet 22, the armature switch 27, its alternate contact, to the upper pole of the battery 11. The magnet 22 is thus maintained in closed 70 circuit, to continue the exclusion of the operator's telephone from circuit relation with the cord. A new circuit is established for the cut-off relay 12 of the called line, to prevent the operation of the line signal 13 75 of such line, which new circuit may be traced from the upper pole of the battery 11, through the winding of said cut-off relay, the thimble of the jack engaging the connecting plug 15, the thimble contact of the 80 connecting plug 15, a contact of the armature switch 34 directly connected with said thimble contact of the plug 15, the armature switch 34, the tip of the connecting plug 85 engaging the jack switch of the called line, and the called line, to the remaining terminal of the battery 11. It will be seen that the circuit of the cut-off relay 12 of the 90 called line has now been placed within the control of the called subscriber. 95

When circuit has been established through the magnet 36, a locking circuit is established therefor, which includes the alternate contact of the armature switch 26, and which may be traced from the upper terminal of 100 the battery 11, said alternate contact of said armature switch 26, the winding of the magnet 36, the sleeve contact of the connecting plug, the sleeve contact of the jack engaging said plug, the impedance coil 10 of the called 105 line, to the remaining pole of the battery 11. The winding 36 is thus included in a local circuit which is within the control of the operator exclusively. The coil 37 is included in a circuit that is governed by the called 110 subscriber, and inasmuch as the position of the armature switch 34 (together with its companion switches 28 and 35) depends upon the deenergization or non-energization of the coil 37, the circuit of the called 115 subscriber's relay 12 is dependent upon the called subscriber.

If the called subscriber should desire to become a calling subscriber, and to that end wishes to get into communication with his 120 own operator, such called subscriber will first restore his telephone receiver to its switch-hook, thereby opening the circuit of the winding 37, thereby to open circuit of the cut-off relay 12. When the circuit of the 125 winding 37 is once opened, it cannot again be closed except in the manner previously specified, the called subscriber being powerless to close a circuit through the winding 37 after he has once opened said circuit. 130

The cut-off relay 12 of the called subscriber, therefore, when once included in open circuit by the release of the armature switch 34, is not again included in closed circuit, except by the operator who responds to the line signal of the called subscriber when he has removed his telephone receiver from its switch-hook after having thrown the windings 12 and 37 out of circuit, as has been described, or by some other operator establishing connection with the called line. Thus the called subscriber renders himself independent of the connection that had existed between him and the calling subscriber, and renders himself independent of the calling subscriber's apparatus, for the purpose of gaining control of his own line signal.

In accordance with my invention, the called subscriber is enabled to dissociate his line equipment from the operator's equipment, it being my purpose to cause the calling subscriber to convey the clearing-out signal, which he does when he restores his telephone to its switch-hook. When the calling subscriber restores his receiver upon his switch-hook, the circuit of relay 18 is opened, permitting its armature to fall back and release circuit through the clearing-out signal 19. The circuit for the clearing-out signal 19 may be traced from the lower terminal of the battery 11, the lamp 19, the armature switch of relay 18 and its normal contact, the thimble contact of the answering plug 14, the thimble contact of the engaged jack, the cut-off relay 12 of the calling line, to the upper terminal of the battery 11. It is thus an important feature of my invention to provide a system wherein the called subscriber may by his own action, without the aid of the calling subscriber, place himself in communication with his own operator, and whereby the calling subscriber is bound to the association of his line with the connecting apparatus, in order that such calling subscriber may convey the clearing-out signal, the calling subscriber's line signal being still dissociated from his line, so that if the calling subscriber should again take off his receiver from its switch-hook, during the connection of a line with the connecting apparatus, the line signal will not be operated, the clearing-out signal thus being operated by vibration of the calling subscriber's switch-hook, to indicate to the operator that her attention is again required by the calling subscriber. A great advantage is afforded by this arrangement, inasmuch as the operator is enabled to notice the disconnect signal much quicker than she would a line signal, and if the calling subscriber should desire connection with another line, such new connection is expedited, as the answering plug is already in connection with the line of the calling subscriber.

65 It will be observed that when the answer-

ing plug is in position, the cut-off relay 12 and the relay 18 are in parallel relation and in series relation with the battery 11, terminals of the relays 12 and 18 being connected with the upper terminal of the battery 11. The joint impedance of the relays 12 and 18 is caused to equal the impedance of the associate impedance coil 10. By this arrangement the battery 11 is included in bridge of the calling telephone line, there being included in this bridge on one side of the battery 11, the impedance coil 10, and in this bridge on the other side of said battery 11, the joint impedance furnished by the relays 12 and 18. The battery 11 is also included in bridge of the called telephone line, the impedance 10 of the called line being included in this bridge upon one side of the battery 11 while the same bridge contains, upon the other side of the battery 11, the joint impedance furnished by the relay winding 37 and the cut-off relay 12 of the called line, these latter elements being also in multiple relation.

I will now describe another feature of my invention, a description of which was omitted hitherto for the sake of clearness in the description of remaining features of my system. In accordance with the present feature of my invention, at least one gap in the cord circuit controlled by the relay windings 31, 37 (preferably the gap controlled by the armature switch 28) is bridged by a path 38 which serves as a conductor of limited capacity for the signaling current (and which conductor may for the purpose include high impedance), so that a small fraction of the signaling current may find its way to the calling subscriber's line, to satisfy the calling subscriber that a call is being sent.

It will be seen that I have provided a common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the battery is disposed, the portions of the battery bridges that are connected with the limbs of the telephone lines through the agency of the connecting apparatus including as impedance, relays that are in parallel, one of the relays in one of the bridges being connected with the connecting apparatus and entering into the control of a clearing-out signal and the other of the relays being connected with a

5 jack switch of the associated line and constituting a cut-off relay for such line, the jack switch and connecting apparatus having contacts adapted for engagement to make and break the parallel connection between said relays.

10 In the claims I speak of the impedance devices connected in parallel or in multiple relation and relays connected in parallel or in multiple relation, meaning thereby that these devices or relays have their terminals conductively or metallically united, so that battery current finds passage from one pair of united terminals to the other pair of united terminals over both devices or relays. In other words, the claims are intended to mean that the impedance devices or relays have common terminals, from one of which to the other of which battery current may flow over both impedance devices or relays, the battery current passing from the said other common terminal on.

15 While I have herein shown and particularly described the preferred embodiment of my invention, I do not wish to be limited thereto, as changes may readily be made without departing from the spirit thereof, but, having thus described my invention, I claim as new and desire to secure by Letters

20 Patent the following:—

25 1. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the 30 battery is disposed, the portions of the battery bridges that are connected with the limbs of the telephone lines through the agency of the connecting apparatus including as impedance, relays that enter into the exchange equipment and are in parallel.

35 2. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the 40 battery is disposed, the portions of the battery

45 bridges that are connected with the limbs of the telephone lines through the agency of the connecting apparatus including as impedance, relays that enter into the exchange equipment and are in parallel, one of the relays being connected with the connecting apparatus and the other of the relays being connected with a jack switch of the associated line, the jack switch and connecting apparatus having contacts adapted for engagement to make and break the parallel connection between said relays.

50 3. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the 55 battery bridges between which the battery is disposed, the portions of the battery bridges that are connected with the limbs of the telephone lines through the agency of the connecting apparatus including as impedance, relays that are in parallel, one of the relays in one of the bridges being connected with the connecting apparatus and entering into the control of a clearing-out signal and the other of the relays being connected with a jack switch of the associated line and constituting a cut-off relay for such line, the jack switch and connecting apparatus having contacts adapted for engagement to make and break the parallel connection between said relays.

60 4. A telephone line, a battery for supplying the same with current and in bridge between the sides of the telephone line, connecting apparatus for connecting said telephone line with another telephone line, said connecting apparatus serving to connect one limb of said telephone line with one end of the bridge conductor containing said battery, the other limb of said telephone line being connected with the other end of said bridge conductor independently of the connecting apparatus, and an impedance device on one side of said battery in said bridge and two impedance devices, in the form of 65 relays, in multiple relation, upon the other side of said battery in said bridge.

65 5. A telephone line, a battery for supplying the same with current and in bridge between the sides of the telephone line, connecting apparatus for connecting said telephone line with another telephone line, said connecting apparatus serving to connect one limb of said telephone line with one end of the bridge conductor containing said bat- 70

tery, the other limb of said telephone line being connected with the other end of said bridge conductor independently of the connecting apparatus, and an impedance device 5 on one side of said battery in said bridge and two impedance devices, in the form of relays that enter into the exchange equipment and are, in multiple relation, upon the other side of said battery in said bridge, one 10 of the relays being connected with the connecting apparatus and the other of the relays being connected with a jack switch of the associated line, the jack switch and connecting apparatus having contacts adapted 15 for engagement, to make and break the parallel connection between said relays.

6. A telephone line, a battery for supplying the same with current and in bridge between the sides of the telephone line, connecting apparatus for connecting said telephone line with another telephone line, said connecting apparatus serving to connect one limb of said telephone line with one end of the bridge conductor containing said battery, the other limb of said telephone line being connected with the other end of said bridge conductor independently of the connecting apparatus, and an impedance device 25 on one side of said battery in said bridge and two impedance devices, in the form of relays, in multiple relation, upon the other side of said battery in said bridge, one of the relays being connected with the connecting apparatus and entering into the control 30 of a clearing-out signal and the other of the relays being connected with a jack switch of the associate line and constituting a cut-off relay for such line, the jack switch and connecting apparatus having contacts adapted 35 for engagement, to make and break the parallel connection between said relays.

7. A common battery telephone exchange system including telephone lines extending from sub-stations to an exchange, connecting apparatus for uniting lines in conversation, a common battery at the exchange adapted to have one terminal connected with one limb of each of the connected telephone lines by said connecting apparatus, 45 the other terminal of said battery being connected with the remaining limbs of said telephone lines independently of said connecting apparatus, an operator's telephone set, a relay having an armature switch, which, 50 when unattracted, serves normally to include the telephone set in bridge of the connecting apparatus, and circuit connections governed by the connecting end of said connecting apparatus, for closing circuit 55 through said relay to remove the operator's telephone set from association with the connecting apparatus, the battery, by having direct connection with only one of the conductors of the connecting apparatus, serving 60 to prevent cross talk that might arise 65

were both terminals of the battery connected with both talking conductors of the connecting apparatus.

8. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the battery is disposed, the portions of the battery bridges that are connected with the limbs of the telephone lines through the agency 80 of the connecting apparatus including impedance devices that are in parallel. 85

9. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the battery is disposed, the portions of the battery bridges that are connected with the limbs of the telephone lines through the agency of the connecting apparatus including impedance 90 devices that are in parallel, one of said impedance devices constituting a cut-off relay. 95

10. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery 100 bridges between which the battery is disposed, the portions of the battery bridges that are connected with the limbs of the telephone lines through the agency of the connecting apparatus including impedance 105 devices that are in parallel, one of said impedance devices constituting a cut-off relay. 110

11. A common battery telephone exchange system including telephone lines extending 115

from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the battery is disposed, the portions of the battery bridges that are connected with the limbs of the telephone lines through the agency of the connecting apparatus including impedance devices that are in parallel, one of the impedance devices being connected with the connecting apparatus and the other of the impedance devices being connected with the jack switch of the associated line, the jack switch and connecting apparatus having contacts adapted for engagement to make and break the parallel connection between said impedance devices.

12. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting apparatus, and impedance devices in the battery bridges between which the battery is disposed, the portions of the battery bridges that are connected with the limbs of the telephone lines through the agency of the connecting apparatus including impedance devices that are in parallel, one of said impedance devices constituting a cut-off relay, one of the impedance devices being connected with the connecting apparatus and the other of the impedance devices being connected with the jack switch of the associated line, the jack switch and connecting apparatus having contacts adapted for engagement to make and break the parallel connection between said relays.

13. A common battery telephone exchange system including telephone lines extending from sub-stations to an exchange, connecting apparatus at the exchange for uniting lines in conversation, a common battery adapted for inclusion in bridges of the telephone lines, said connecting apparatus serving to connect one terminal of the battery with one limb of each telephone line, the other terminal of said battery being connected with the remaining limb of each telephone line independently of said connecting

apparatus, and impedance devices in the battery bridges between which the battery is disposed, the portions of the battery bridges that are connected with the limbs of the telephone lines through the agency of the connecting apparatus including impedance devices that are in parallel, one of said impedance devices constituting a cord signal relay, one of the impedance devices being connected with the connecting apparatus and the other of the impedance devices being connected with the jack switch of the associated line, the jack switch and connecting apparatus having contacts adapted for engagement to make and break the parallel connection between said relays.

14. A multiple switch-board system including telephone lines extending from stations to an exchange, line signal devices for said telephone lines, cut-off relays for excluding said line signal devices from operative relation with the telephone lines, connecting apparatus for uniting lines in conversation and serving to operate the cut-off relays to remove the line signal devices from association with the telephone lines, apparatus governed by the called line for removing the control of the connecting apparatus over the cut-off relay of the called line and to restore the control of said cut-off relay to the called line, and a clearing-out indicator in association with the connecting apparatus and having its association with the calling line governed by the connecting apparatus, the cut-off relay of the calling line being governed by the connecting apparatus exclusively of the calling line, whereby said clearing-out indicator may be operated by the calling line without causing the line signal of the calling line to be displayed during the time that the connecting apparatus is associated with the calling line.

15. A telephone exchange system including telephone lines extending from stations to an exchange, connecting apparatus for uniting lines in conversation, a switch for making and breaking a conductor of said connecting apparatus, a relay governing said switch and energized, when the called party responds, to cause said switch to complete the conductor whose continuity is governed by said switch, a source of signaling current adapted for connection with the called telephone line on a side of said switch toward the called telephone line, and a connection bridging the gap controlled by said switch between the sections of said conductor and forming a path which is partially opaque to current from said source, whereby a limited quantity only of calling current is permitted to pass to the calling line, to indicate to the calling party that the called party is being signaled.

16. A telephone exchange system including telephone lines extending from stations

- to an exchange, line signal devices for said telephone lines, cut-off relays for excluding said line signal devices from operative relation with the telephone lines, connecting 5 apparatus for uniting lines in conversation and serving to operate the cut-off relays to remove the line signal devices from association with the telephone lines, apparatus governed by the called line for removing 10 the control of the connecting apparatus over the cut-off relay of the called line and to restore the control of said cut-off relay to the called line, and a clearing-out indicator in association with the connecting apparatus 15 and having its association with the calling line governed by the connecting apparatus, the cut-off relay of the calling line being governed by the connecting apparatus exclusively of the calling line, whereby said 20 clearing-out indicator may be operated by the calling line without causing the line signal of the calling line to be displayed during the time that the connecting apparatus is associated with the calling line. 25 17. A telephone exchange system including telephone lines extending from stations to an exchange, line signal devices for said telephone lines, connecting apparatus for uniting lines in conversation, means where- 30 by the signals occasioned by said line signal devices may be effaced when calls are answered at the exchange, apparatus governed by the called line for removing the control of the connecting apparatus over the line 35 signal of the called line during connection of the called line with the connecting apparatus, and a clearing-out indicator in association with the connecting apparatus and having its association with a calling line 40 governed by the connecting apparatus, the means for controlling the line signal of the

calling line being governed by the connecting apparatus exclusively of the calling line, whereby said clearing-out indicator may be operated by the calling line without caus- 45 ing the line signal of the calling line to be displayed during the time that the connecting apparatus is associated with the calling line.

18. A multiple switch-board system in- 50 cluding telephone lines extending from stations to an exchange, line signal devices for said telephone lines, connecting apparatus for uniting lines in conversation, means whereby the signals occasioned by said line 55 signal devices may be effaced when calls are answered at the exchange, apparatus governed by the called line for removing the control of the connecting apparatus over the line signal of the called line during con- 60 nection of the called line with the connecting apparatus, and a clearing-out indicator in association with the connecting appa- 65 ratus and having its association with a calling line governed by the connecting appa- 70 ratus, the means for controlling the line signal of the calling line being governed by the coneting apparatus exclusively of the calling line, whereby said clearing-out indi- 75 cator may be operated by the calling line without causing the line signal of the calling line to be displayed during the time that the connecting apparatus is associated with the calling line.

In witness whereof, I hereunto subscribe 75 my name this sixteenth day of January
A. D., 1909.

ELMER R. CORWIN.
